UNITED STATES PATENT OFFICE.

FRANCIS M. CROSSMAN, OF NEW YORK, N. Y.

DRIER FOR BRIQUETTES AND OTHER AGGLOMERATES.

Application filed March 17, 1925. Serial No. 16,183.

This invention relates to briquette driers. I have found in practice that the driers now in use leave much to be desired in the way of efficiently drying the briquettes. These 5 driers are expensive to build and complicated and costly to operate. It is an object of the present invention to overcome these objections by providing a drier that is simple in construction, economical to operate and efficient in drying the briquettes.

Another feature of the invention is the provision of means for regulating the entrance of the drying gases into the drier to prevent the possibility of the drying chambers becoming too hot with resultant damage to the briquettes.

Another feature is the provision of devices for permitting the entrance of cool air into the drying chambers.

Still another feature is the provision of easily operated unloading means for unloading in case of emergency or for cleansing purposes.

The invention accordingly consists in the features of construction, combination of elements and arrangement of parts which will be exemplified in the construction herein-after set forth and the scope of the application of which will be indicated in the following claims.

In the accompanying drawings forming a part of this specification wherein similar reference characters refer to similar parts throughout the several views,

Figure 1 is a central vertical sectional view of my improved drier, and

Figure 2 is a plan view thereof.

Referring to the drawings, illustrating the preferred embodiment of my invention, 40 the drier proper comprises a metal drum 1 formed preferably of steel, which drum is mounted solidly on a steel structure 2. Said steel structure 2 is supported by four concrete piers 3, leaving considerable space between the floor of the drum and the floor or other surface upon which the piers 3 rest.

As will be seen from Figure 1, the drum 1 is formed with a plurality of compartments 4, through which the briquettes pass as will be explained herein-after. Passing through the center of the drum 1 is a shaft 5, the bottom end thereof resting in a bearing block 6, said shaft being adapted to revolve in its bearings. Fixed to the shaft 5 in each of the compartments 4 are radial arms 7, which arms are adapted to move the

briquettes in the compartments 4. The driving means for rotating the shaft 5 are illustrated as a worm 8, meshing with a gear 9 mounted on a shaft carrying a pinion 10, which pinion 10 drives a gear 11 secured on the shaft 5. Of course, any other desirable driving means may be used.

The floor of each compartment 4 is provided with an opening 11^a through which the briquettes pass to the compartment 4 immediately below, it being understood that the said openings 11^a are arranged in staggered relationship so that no two of them are in alignment and so that the briquettes are successively carried through each compartment 4 until they reach the discharge opening in the drum 1.

The driving gears for the shaft 5 are driven by the motor 11^a, pulley 11^b and belt 11^c which are operatively connected thereto as will be seen from Figure 2.

The drum 1 is surrounded by a space or chamber 12, which chamber 12 is in communication with the passageway 12^a leading from a furnace 13 to said chamber 12, by means of ducts 14 and 15. It will be understood that the hot gases pass from said furnace 13 through said passageway 12^a and ducts 14 and 15 to the chamber 12 for drying the briquettes in the drum 1. The products of combustion produced by the furnace 13 escape up the stack 16 by means of the duct 17 leading from the furnace to said stack.

In order to regulate the entrance of the hot gases into the chamber 12, at certain points in the ducts 14 and 15 are mounted dampers 18 and 19, respectively.

Formed in the periphery 20 of the drum 1 are rows of holes 21, which holes open into the compartments 4.

Arranged directly opposite the ducts 14 and 15 and communicating with the chamber 12 is an outlet duct 22, through which the hot gases pass to a stack 23. Mounted in said stack 23 is a damper 24 to regulate the discharge of the gases.

Disposed between the drum and the stack 23 and operatively connected to the duct 22 is a fan 25 driven by a motor 25^a, which fan facilitates the passage of the hot gases.

Surrounding the drum 1 is a cylindrical casing formed of steel or other suitable metal. Formed in said casing at each side of the inlet ducts 14 and 15 is a hinged door 26, and formed in the wall of the drum 1 at points opposite said doors 26 and in align-

ment therewith are doors 27. Proper insulating material such as brick 28 is used for lining the inside of the casing.

In order to regulate the exit of the hot gases from the chamber 12 to the discharge duct 22, on each side of the opening into the duct 22 is mounted a damper 29.

The briquettes or other material is fed to the drum 1 by means of conveyer 30 shown here as an endless belt. The briquettes on the conveyer are carried to and discharged upon a chute 31, said material being carried toward the chute 31 in buckets 32 or other carrying members.

Mounted in the shaft 5 adjacent the top of the drum 1 and adapted to rotate therewith are radial arms 33. These arms 33 in their turning movement carrying the briquettes, which slide down the chute 31 and through an opening 34 in the top of the drum 1, around with them until said briquettes fall through an opening 11^a as explained before. The briquettes are carried around in the compartments 4 by means of the radial arms 7 until they fall through the openings 11^a in the successive compartments and upon falling through the opening 11^a in the lowermost compartment 4 the briquettes are discharged upon a chute 35 which leads to any suitable vehicle for carrying the material away.

In practice, should the temperature in the drier become too hot and there is danger of the briquettes becoming cooked or burned, all that it is necessary to do is to shut the

dampers 18 and 19 in the ducts 14 and 15, respectively, open the doors 26 and 27 and turn on the fan 25 and an ample supply of cool air will be admitted. The closing of the dampers 29 also provides an additional means for promoting the circulation of the air through the chamber and drum.

In case it is desired, due to cleansing the drier or for some emergency, to empty the briquettes from the drum all that it is necessary to do is to open the doors 26 and 27.

It will be obvious to those skilled in the art to which the invention relates that modifications may be made in details that will not depart from the spirit of the invention and I do not desire to limit myself to such matters otherwise than is necessary owing to the prior state of the art and the appended claim.

I claim:

In a drier having a series of vertical drying chambers and a hot gas chamber surrounding said series of vertical drying chambers, means for the admission of hot gases and means for the exhaust of hot gases and a plurality of doors vertically disposed in the walls of said series of vertical chambers and said hot gas chamber, said doors opening externally of said apparatus for the admission of cool air or the unloading of material in said vertical chambers.

Signed at New York, in the county of New York and State of New York, this 15th day of March, A. D. 1925.

FRANCIS M. CROSSMAN.
